(57) CLAIM

I claim the ornamental design for a front panel of a merchandise display, as shown and described.

DESCRIPTION

FIG. 1 is a perspective view of a front panel of a merchandise display of the present claimed design;

FIG. 2 is a front view of the front panel of the merchandise display shown in FIG. 1; and,

FIG. 3 is a side view of the front panel of the merchandise display shown in FIG. 1, the opposite side view being identical thereto.
